UNITED STATES PATENT OFFICE

130,451

DESIGN FOR A CAMERA

Michael Krieger, Los Angeles, Calif.

Application March 19, 1941, Serial No. 99,704

Term of patent 3½ years

To all whom it may concern:

Be it known that I, Michael Krieger, a citizen of the United States and residing at Los Angeles, in the county of Los Angeles, State of California, have invented a new, original, and ornamental Design for a Camera, of which the following is a specification, reference being had to the accompanying drawing, forming part thereof, in which:

Fig. 1 is a perspective view of a camera in a partly telescoped position as seen from one side

and the front thereof showing my new design:

Fig. 2 is a perspective view of the camera in a partly telescoped position as seen from the side thereof opposite that shown in Fig. 1 and showing the top and rear thereof:

Fig. 3 is a front elevational view thereof.

I claim:

The ornamental design for a camera, as shown.

MICHAEL KRIEGER.
